WILLIAM D. HAILES, OF ROCHESTER, NEW YORK, ASSIGNOR TO GENERAL RAILWAY SIGNAL COMPANY, OF ROCHESTER, NEW YORK

CONTINUOUS INDUCTIVE TRAIN-CONTROL SYSTEM

Application filed July 20, 1929. Serial No. 379,639.

This invention relates in general to coded inductive train control systems, and has more particular reference to systems employing so called rate or frequency or non-pattern types of codes such, for example, as disclosed in the Hailes application 228,058, filed October 22, 1927, and entitled Continuous train control systems.

In train control systems of the character referred to above, car-carried apparatus is employed which is inductively affected by coded train control current in the track rails to set up distinctive cab signals in accordance with the particular code applied to the track rails. The codes comprise alternate applications of current to the track rails and removal of such current from the track rails, and these codes are primarily differentiated by the number of separate applications of 20 energy per unit of time.

It is obvious that it is possible, due to vibrating grounds, or broken wires, either on the trackway or on the car, that a code might be set up regardless of traffic conditions so as 25 to cause the system to show a favorable indication. For example, under danger conditions, when no code should be applied to the track rails, such a vibrating ground might set up a code rapid enough to cause a green, 30 or proceed, indication in the cab.

With the above and other considerations in mind, it is proposed, in accordance with this invention, to provide a code controlled equipment which distinctively responds to 35 rate type codes, and at the same time is protected against showing false favorable indications, particularly a proceed indication, in response to codes due, for example, to vibrating grounds or broken wires or the like.

More specifically, it is proposed to provide 40 means requiring a relatively prolonged interruption of application of train control current to the track rails, at frequent intervals, for the car-carried apparatus to selectively 45 respond to the code for setting up favorable cab indications. The car-carried apparatus is so arranged that the failure of this prolonged removal of current, or blank, intermittently occurring in the code, results either 50 in a R or stop indication, or in a dark signal, even though the code rate be fast enough to normally set up a proceed indication.

A similar problem, is solved in connection with cyclic or pattern or counting types of decoding means, in the Hailes application, 55 Ser. No. 379,638, filed of even date herewith, and entitled Continuous inductive train control systems.

Further objects, purposes and characteristic features will appear as the description 60 progresses, reference being made to the accompanying drawing showing, solely by way of example, and in no manner in a limiting sense, one form which the invention can assume. In the drawing:—

Fig. 1 is a diagrammatic view of one form 65 of car-carried apparatus embodying the present invention.

Fig. 2 is a diagrammatic view showing a 70 number of codes which can be employed in connection with the apparatus of Fig. 1, together with a showing of how the apparatus responds to the proceed or G code.

Fig. 3 is a diagrammatic view of a frequency code, such as might be produced by a 75 vibrating ground, and shows how the apparatus is immune to such a code, to avoid setting up a favorable indication.

Referring now to the drawing, and first to Fig. 1, in which the apparatus is shown in the 80 condition assumed under stop conditions, when no train control current is on the track rails, and the R, or stop indication is displayed in the cab, there is here shown a stretch of track constituted by track rails 1, 85 on which is a train as indicated by the wheels and axle 10. The train carries in advance of the foremost wheels and axle, receiving coils 12, positioned to be inductively affected by currents circulating in the rails 1. The receiving coils 12 are connected up in series, together with a tuning condenser 13 and the primary of a transformer 14, the secondary of transformer 14 being connected in series 90 with a tuning condenser 16 and the primary 95 of a transformer 15. The secondary of transformer 15 is connected to the input side of an amplifier A, with the output side of amplifier A connected to a coding primary relay, CPR, having contact fingers 40 and 41. 100

The apparatus just described, and much of the apparatus still to be described, with the exception of the decoding means, is substantially the same as disclosed in the Hailes application 228,058, referred to above, and accordingly only a very brief description of these parts is necessary in this application for a proper understanding of the present invention.

With the receiving apparatus above described, it is clear that relay CPR follows the application and removal of current to and from the track rails so as to pick up and release in accordance with whether train control current is on or off the track rails, current being applied and removed in accordance with chosen codes, such as G, Y/G, Y and R as shown in Fig. 2, by any usual or desired coding means, as in application Ser. No. 20 228,058, located along the wayside.

Included in the decoder of this invention is a bank of relays including R¹, having a contact finger 42, which is quick to pick up but has a release time of approximately 4 seconds; a relay R², having contact fingers 43 and 44, which is quick to pick up but has a release time of approximately .5 seconds; a relay R³, with contact fingers 45 and 46; a relay R⁴ having contact fingers 47, 48 and 49, and a relay R⁵ having contact fingers 50, 51 and 52, the relays R²—R⁵ each being quick to pick up and each having a release time of approximately 2 seconds.

The contact finger 40, of relay CPR which follows the code, operates to put energy on one-half of the primary of a transformer T, when picked up, and to likewise energize the other half of the primary of transformer T, in a reverse direction, on release, there being a condenser 53 connected across the primary of transformer T. This operation results in transferring energy to the secondary of transformer T on each make, and each break, of contact by finger 40 of relay CPR.

The relays R³—R⁵ are each connected across a different number of turns of the secondary of transformer T, through a tuned circuit including a double wave rectifier whereby to energize each relay with uni-directional current, and to permit ready flow of energy only at a certain frequency, namely the frequency for which each relay input circuit is tuned to resonate. For example, relay R⁵ is connected across the cut-put side of a rectifier Rec⁵, the input side of which rectifier is connected across the secondary of an auto-transformer T⁵, the primary of which transformer is connected in series with a tuning condenser C⁵, a number of turns of the secondary of transformer T, and contact finger 44 and front point of relay R².

In a like manner, relays R⁴ and R³ are energized through like tuned circuits, corresponding reference characters with distinctive exponents being employed to identify the

corresponding parts in these circuits and connections.

In the particular form of invention employed for illustration in this application, codes such as shown in Fig. 2 are used, according to which spaced impulses of current are placed on the track rails 1 at the rate of 180 per minute for the G code, at the rate of 120 per minute for the Y/G code, and at the rate of 80 per minute for the Y code. As indicated in Fig. 2, stop, or R is given by current either steady on, or steady off.

Thus the G code corresponds to three cycles of alternating current per second, the Y/G code to two cycles of alternating current per second, and the Y code to one and one third cycles of alternating current per second. The circuit for relay R⁵ is tuned to resonance at a frequency of three cycles per second and the circuit for relay R⁴ is tuned to a resonance at a frequency of two cycles per second, while the circuit for relay R⁵ is not tuned to any particular frequency but allows passage of current having a frequency of any of the various codes. In this manner the G code causes energy from the secondary of transformer T to pick up relay R⁵ and also R³, but not relay R⁴. The Y/G code operates to pick up relays R⁴ and R³, but not relay R⁵. The Y code operates to pick up relay R³ but not relays R⁴ or R⁵.

The picking up of contact finger 41 of coding primary relay CPR operates to pick up relay R² through a circuit obvious in the drawing, while relay R¹ is energized through a circuit including contact finger 43 and back point of relay R² and upon once being picked up, holds up for approximately four seconds after its circuit is opened.

The various relays R¹—R⁵ just described operate through their various contact fingers to place energy, at any one time, on but one of the wires g, y/g, y and r, depending on the particular code being received. If the G code, that is, the 180 per minute rate code, is being received, energy is placed on the g wire and likewise for the other codes, energy being placed on the r wire when no code is being applied but train control current is either steady on or steady off.

The various codes used in connection with the decoder described above, are rate codes, as diagrammatically illustrated in Fig. 2, but these rate codes include intermittent off or blank periods of relatively long duration, for example, .8 seconds in the particular case chosen. It is necessary that a rate code include these long blank periods at frequent intervals, in order that the decoder of this invention properly respond.

This is clear when we consider that energy for the wires g, y/g and y must all pass through contact finger 42 and front point of relay R¹, and that it is necessary, for relay R¹ to be up, that at least every four seconds

this relay R^1 be energized through contact finger 43 and back point of relay R^2 .

Since relay R^2 is picked up on the first impulse of current, and has a release time of .5 seconds it is clear that a blank of greater duration than .5 seconds must occur at least every four seconds in the particular example chosen, or otherwise relay R^1 releases to take energy off of all the favorable indication wires, and place it on wire r either to give an R or stop indication, or to leave the entire cab signal de-energized, dependent upon the then conditions of relays R^4 and R^5 . That is, a rate code having no prolonged blank, but of such a rate as to pick up either of the relays R^4 or R^5 , results in R^1 down and R^4 or R^5 or both up, to cut energy off of all the wires $g-r$ and leave the cab signal dark. If, however, the code be of such a rate as to leave R^4 and R^5 down, the R or stop indication is displayed.

Considering now a specific example, when the proceed, or G code is placed on the track rails 1, primary relay CPR picks up and releases in accordance with the code to place three cycle frequency current on the secondary of transformer T and operate to pick up relays R^3 and R^5 , but not to pick up relay R^4 .

Before the G code was started, relay R^2 was down to thereby energize relay R^1 , and since the sending time, 3.0 seconds in the present case, is less than the four second release time for relay R^1 , before it can release, a blank period occurs, (in the present case .8 seconds) long enough to drop relay R^2 and thus re-energize relay R^1 to hold relay R^1 up continuously. It should be noted that the release times for the relays R^3-R^5 is long enough to at least cover the blank portions of the codes, so as to prevent their releasing.

In this manner, the G code, as shown in Fig. 2, which is in effect an intermittent rate type code, results in relays R^1 , R^3 and R^5 being picked up and maintained picked up all the time the code is being transmitted, to thereby place energy continuously on the g wire through a circuit including, contact finger 42 and front point of relay R^1 , contact finger 45 and front point of relay R^3 , contact finger 47 and back point of R^4 and contact finger 50 and front point of relay R^5 .

In a like manner, when the Y/G, or approach restricting code, having a rate of 120 cycles per minute, i. e. 2 cycles per second, is applied, relays R^3 and R^4 are picked up and held up, but relay R^5 is not energized and so releases, whereby to place energy on the y/g wire through a circuit including contact finger 42 and front point, contact finger 45 and front point, contact finger 50 and back point, and contact finger 47 and front point.

A similar operation in connection with the caution, or Y, code, places energy on the y wire through a front point R^1 and R^3 and a back point of R^4 and R^5 .

When no code is being applied to the track

rails there is normally no current of train control frequency on the rails, and this operates to place energy on the r wire to set up a stop indication in the cab, since, with no energy being received by the receivers 12, all of the relays R^1-R^5 are de-energized. Also, if current is steadily applied to the rails 1, relay CPR is held steadily up, to de-energize all of the decoding relays except R^2 , which again results in completing the circuit for placing energy on the wire r , which circuit includes contact fingers 42, 49 and 52 and their respective back points, of relays R^1 , R^4 and R^5 .

Referring now to Fig. 3, should a rate type code be accidentally applied to the track rails, or applied to the primary relay CPR, as for example by a vibrating ground or broken wire or in any other manner, energy of a particular frequency, depending on the rate of the accidentally produced code, will be applied to the secondary of transformer T and may operate relays R^1-R^5 to temporarily apply energy to any one of the wires g , y/g or y .

In the absence of a blank, however, such as could not very well be present in the hypothetical code under consideration, after a short time, such as 4 seconds, relay R^1 will release, and since relay R^2 will be held up continuously, relay R^1 will stay down to thereby make it impossible to put energy on any of the favorable indication wires g , y/g and y . As a result, such a code as just considered, will set up either a dark signal in the cab, or an R signal, depending on the condition of relays R^4 and R^5 . If the frequency of the code in question is fast enough to pick up either R^4 or R^5 , as is true in Fig. 3, a dark cab signal results, whereas if it is so slow as to not pick up either R^4 or R^5 , then a stop or R indication is set up in the cab.

In the above manner, it is clearly to be seen how a rate type decoder is provided which is immune from responding to rate type codes lacking intermittent extended blanks, to set up favorable indications, and since an accidentally produced rate type code is conceivable, but the accidental production of a rate type code including intermittent extended blanks, such as shown in Fig. 2, is inconceivable, provision has been made, to the highest degree, against accidental operation of the decoder.

The manner in which a rate type code of 120 for example 180 applications per minute, conceivably producable by a vibrating ground or broken wire or the like, is incapable of operating the decoder described above, is set forth graphically in Fig. 3, and is believed self-explanatory.

In the above discussion, it has been shown how the decoder operates, in accordance with various codes, to selectively respond and place energy on one only of the wires g etc.

These wires can, if desired, be directly connected to a cab signal, but it is preferable that there be inserted before the cab signal, a group of relays constituting a delay means, and a group of relays constituting an acknowledging group, together with acknowledging and reset contactors, brake applying means EPV, and audible signal means AWV, for advising that acknowledgment should be performed, all as disclosed in the Hailes application 228,058 above referred to.

The delay group of relays, includes a relay GR, energized through the *g* wire, a relay Y/G—R energized through the *y/g* wire, a relay YR, energized over the *y* wire, and a relay RR, energized over the *r* wire, each of these relays receiving its energy through a back point of each of the other relays of the group whereby to permit energization of only one relay of this group at any one time.

The acknowledging group of relays includes stick relays SR, SY, and S—Y/G whereby to enforce acknowledgment on going into more restrictive territory, such acknowledgment being advised by the audible signal AWV. If acknowledgment be not performed within the prescribed period, a brake control relay BR, releases to thereby de-energize the electro-pneumatic device EPV, which, when de-energized, operates to apply the brakes, as well recognized by those skilled in this particular art.

As in the Hailes application 228,058 above referred to, acknowledgment silences the whistle AWV and prevents an automatic brake application if performed in due time. If acknowledgment is not properly performed, an automatic brake application results and it is then necessary to bring the train to a full stop in order to operate a reset device Res, which is accessible only from the ground, for permitting release of the brakes and resumption of progress.

A detailed description of the operation of the delay group of relays, of the acknowledging group of relays, and of the brake applying means and reset means is believed wholly unnecessary in this application, since it is substantially identical with the Hailes application 228,058 above referred to, and is not necessary for a complete understanding of the present invention.

The various times for release chosen for the decoding relays, and other relays, in this invention can of course be varied to any extent desired, as can likewise be varied the rates of the various codes to be employed therewith, it being merely necessary that the various times chosen be proper for satisfactory cooperation between the applied codes and the decoding and secondary means employed for responding to the codes and setting up proper cab indications, brake controls etc. In other words, the particular times of the various codes and relays in this invention are given

merely by way of example, and are not to be considered, in any manner, a limitation.

The above rather specific description of one form of system embodying the present invention, has been given solely by way of illustration, and is not intended, in any manner whatsoever, in a limiting sense. Obviously, this invention can assume many different physical forms, and is susceptible of numerous modifications, and all such forms and modifications are desired to be included by this invention, as come within the scope of the appended claims.

Having described my invention, I now claim:—

1. In a coded continuous train control system, in combination with a receiver for receiving coded energy and secondary circuits for controls of varying restrictiveness, a decoder connected between said receiver and secondary circuits, and responsive to various frequency codes in a selective manner which is dependent upon the number of separate impulses of energy per unit of time in the different codes, to selectively set up said controls, and means in said decoder for preventing it setting up a favorable indication in response to code unless such code is intermittently interrupted for a relatively long time interval.

2. In a coded train control system, in combination with a receiver for coded energy and secondary circuits for controls of varying restrictiveness, a decoder connected between said receiver and secondary circuits, and responsive to various frequency codes in a selective manner, dependent upon the number of separate impulses of energy per unit of time in the different codes, to selectively set up said controls, and means in said decoder for preventing it setting up a favorable indication in response to code unless such code is intermittently interrupted by a blank or current-off period for a relatively long time interval.

3. In a coded train control system, in combination with a receiver for coded energy and secondary circuits for controls of varying restrictiveness, a relay decoder connected between said receiver and secondary circuits, and responsive to various frequency codes in a selective manner, dependent upon the number of separate impulses of energy per unit of time in the different codes, to selectively set up said controls, and relay means in said decoder for preventing the decoder setting up a favorable indication in response to code unless such code is intermittently interrupted by a blank or current-off period of considerable length.

4. In a coded continuous train control system, in combination with a receiver for coded energy, and secondary circuits for controls of varying restrictiveness, a decoder connected between said receiver and secondary

circuits, and responsive to various frequency codes in a selective manner, dependent upon the number of separate impulses of energy per unit of time in the different codes, to selectively set up said controls, and monitor relay means in said decoder which by controlling energy supply to said secondary circuits prevents the decoder setting up a favorable indication in response to code unless such code is intermittently interrupted for a time interval which is long relatively to the spaces between the said separate impulses.

5. In a coded continuous train control system, in combination with a receiver for coded energy, and secondary circuits for controls of varying restrictiveness, a decoder connected between said receiver and secondary circuits, and capable of distinguishing between various frequency codes in a selective manner, dependent upon the number of separate impulses of energy per unit of time in the different codes, to selectively set up said controls, and monitor relay means in said decoder controlling energy supply to said secondary circuits for thus preventing the decoder setting up a favorable indication in response to code unless such code is intermittently interrupted for a considerable time interval, said monitor relay means having a front and a back point and controlling the secondary circuit for the most restrictive indication through one of its points, and the other secondary circuits through its other point.

6. In a coded continuous train control system, in combination with a receiver for coded energy, and secondary circuits for controls of varying restrictiveness, a decoder connected between said receiver and secondary circuits, and responsive to various frequency codes in a selective manner, dependent upon the number of separate impulses of energy per unit of time in the different codes, to selectively set up said controls, and monitor relay means in said decoder for controlling energy supply to said secondary circuit for preventing the decoder setting up a favorable indication in response to code unless such code is intermittently interrupted for a time interval relatively long compared to the normal spacing between said impulses, said monitor relay means having a front and a back point and controlling the secondary circuit for the most restrictive indication through its back point, and the other secondary circuits through its front point.

7. A decoder for coded continuous train control systems which includes receiving means and a primary relay for controlling the decoder, and secondary circuits controlled by the decoder, said decoder including a plurality of decoding relays selectively responsive to rate type codes to selectively control said secondary circuits, and a moni-

tor relay controlling energy supply to each of said secondary circuits and having an energizing circuit controlled by a decoding relay.

8. A decoder for coded continuous train control systems including receiving means and a primary relay for controlling the decoder, and secondary circuits controlled by the decoder, said decoder including a plurality of decoding relays some of which have variously tuned energizing circuits, selectively responsive to rate type codes to selectively control said secondary circuits, and a monitor relay for controlling energy supply to each of said secondary circuits and having an energizing circuit controlled by a decoding relay.

9. A decoder for coded continuous train control systems including receiving means for controlling the decoder and secondary circuits controlled by the decoder, said decoder including a plurality of decoding relays, some of which have variously tuned energizing circuits, selectively responsive to rate type codes to selectively control said secondary circuits and a monitor relay for controlling energy supply through a front point to each of the lesser restrictive of said secondary circuits and having an energizing circuit controlled by a front point of a decoding relay having a release time long enough to bridge over the normal spaces between successive code impulses.

10. A decoder for coded continuous train control systems, including, a primary relay connected to successively pick up and release to thus follow a code being received, a control relay directly energized through a finger of the primary relay, and a plurality of relays having variously tuned energizing circuits controlled by the primary relay to thereby variously respond to different codes to selectively set up control circuits of varying restrictiveness, and a monitor relay energized through a circuit controlled by said control relay and in turn controlling energy supply to said control circuits.

11. A decoder for coded continuous train control systems, including, a primary relay connected to successively pick up and release to thus follow a code being received, a control relay directly energized through a finger and front point of the primary relay, and a plurality of relays having variously tuned energizing circuits controlled by the primary relay, to thereby variously respond to different codes to selectively set up control circuits of varying restrictiveness, and a monitor relay energized through a circuit controlled by a front point of said control relay and in turn controlling energy supply to the most restrictive of said control circuits through a back point, and through a front point controlling the other of said control circuits.

12. A decoder for coded continuous train control systems, including, a primary relay connected to successively pick up and release to thus follow a code being received, a control relay directly energized through a finger of the primary relay, and a plurality of relays having variously tuned energizing circuits controlled by the primary relay, to thereby variously respond to different codes to selectively set up control circuits of varying restrictiveness, and a slow release monitor relay energized through a circuit controlled by a back point of said control relay and in turn controlling energy supply to said control circuits.
13. A decoder comprising a plurality of inter-related relays arranged to set up, and to energize secondary control circuits for controlling indications of various restrictiveness, said relays being arranged to selectively distinguish between the rate of application of spaced energy impulses constituting the codes, to selectively set up and energize the control circuits, and means included by the decoder for preventing the energization of a set-up control circuit other than the most restrictive, unless the code be intermittently interrupted for periods of time long relatively to the spaces between said energy impulses.

30 In testimony whereof I affix my signature.
WILLIAM D. HAILES.
